POWER HAMMER

Harry E. Gibson, Muskegon, Mich.

Application December 5, 1949, Serial No. 131,221

4 Claims. (Cl. 153—21)

1

This invention relates to a power hammer which is used in practice in sheet metal joint forming, and with which a rapid forming of a uniform joint may be made between sheet metal parts which are required in many different structures, the connected sheet metal parts being located in planes at an angle to each other and most frequently substantially at right angles to each other.

The present invention is directed to improvements in the joint forming device disclosed in my pending application for patent, Ser. No. 40,672, filed July 26, 1948, now abandoned. In the present invention the force of the hammering movement is provided positively without the necessity of loading any spring which, upon its release supplies the hammering force, springs being eliminated and the immediate hammer given momentum by a direct operation of a rapidly rotating and specially constructed actuator, the hammer being withdrawn and projected once in each complete rotation of the actuator which is mounted on a shaft and is rapidly driven. With the structure a rapid succession of hammer blows are delivered so that the bending and forming and hammering of the sheet metal parts which are processed takes place progressively as the tool is manually moved along the sheet metal members, adjacent edge portion on which are bent and interlocked to form the desired joint. The hammer blows are of equal strength and the joint or seam is made of a substantially uniform quality throughout its length.

An understanding of the invention may be had from the following description, taken in connection with the accompanying drawing, in which

Fig. 1 is an elevation partly in vertical section of the metal joint power hammer tool of my invention, the tool being shown vertically positioned and the mechanism at the lower portion thereof being in transverse vertical section.

Fig. 2 is a fragmentary elevation of the hammer actuator with the associated means on the hammer in section, when it has been withdrawn by the actuator farthest away from the work which is being done, and,

Fig. 3 is a similar view of the relative positions of such parts when the hammer has been projected toward the work which it is to accomplish, the actuator having moved rotatively a short distance beyond the position shown in Fig. 2.

Like reference characters refer to like parts in the different figures of the drawing.

Within the housing 1 at an end of the enclos-

ing body or casing of the machine an electric motor 2 is located, the shaft 3 of which, at its outer end, is formed with parallel pinion teeth meshing with a gear 4 at an end of a short shaft 5, the axis of which is parallel to the axis of the motor shaft 3 and which is mounted in suitable bearings at opposite end portions and which between its ends carries an actuator 6. The actuator 6 is of a cylindrical form and has around it between its ends a groove 7. The major portion of the groove is in the same plane, but at one side a cam projection 8 extends toward the other side of the groove into a cooperating recess 9 of concave form, one side of the projection 8 being inclined as indicated at 8a, the inclined side of said projection 8 moving ahead of the other or straight back side of said projection in the direction of rotation of the actuator, such direction of rotative movement being indicated by arrows in the figures of the drawing. The groove 7 is narrowed at 7a at the free end portion of the projection 8 as shown.

A shaft 10 is mounted for a limited longitudinal movement at a side of the actuator, its axis being parallel to the axis of the shafts 3 and 5. The outer portion 10a of the shaft 10 is interiorly bored to provide a cylindrical axial opening, such portion of the shaft extending from its outer end nearly to a collar 11, integral with or permanently secured to the shaft 10, which is formed with beveled or inclined upper or lower faces in correspondence with similar beveled inclined upper or lower sides of the groove 7 in the actuator. The collar 11 extends into the groove 7.

The outer end portion of the axially bored section 10a of the shaft 10 is interiorly threaded to receive a nut 12 as shown in Fig. 1. The hammer head 13 is connected with a rod 14 which extends axially and freely through the nut 12, its inner end being screw threaded and having a member 15 screw connected thereto and adjustable thereon, between the outer end of which and the inner end of the nut 12 a short coiled compression spring 16 is located around the rod 14. The member 15 is free to move longitudinally within the axial opening of the portion 10a of the shaft 10. The shoe 17 together with head 13 and other parts adjacent are like those shown in my prior application, reference to which is made above. The enclosing housing 18 in which the several shafts are located and mounted, the shaft 10 at its outer portion extending beyond said housing, is made up of suitable sections for convenience in assembling as shown, connected together, and at one side thereof a handle 19 for

grasping by the hand is permanently secured and extends outwardly therefrom, to which wires leading to its motor 2 are carried through a suitable insulation covered cable 20 to supply the motor with electric current.

In the operation, the actuator 6 is rotated at a relatively high speed but at a reduced speed compared to the revolutions per minute of the motor shaft 3. The shaft 10 upon the rotation of the actuator 6 in the direction indicated by the arrows, on each revolution thereof brings the camside 8a of the cam projection 8 to the collar 11 whereupon the projection 8 moves the collar to substantially the position shown in Fig. 2. On the continued movement of the actuator in the direction indicated, the curved side or edge of the recess 9 engaging said collar, because of the high rotative speed, throws said collar and the attached shaft and the hammer 13 with considerable force at the outer end thereof from the position shown in Fig. 2 to that shown in Fig. 3, the projection 8 moving away from the edge of the collar 11 which extends into the groove 7. The momentum of the head 3, the rod 14 to which it is connected and the member 15 causes a quick and sharp blow to be struck by the head 13 upon the work which is being processed. Such blow is cushioned by the spring 16 and after the blow is struck and the work has been done by that particular stroke of the hammer, the head is slightly withdrawn from the work until, on the next succeeding rotation of the shaft 5 and the actuator connected thereto, the operation is repeated.

With the structure described no spring is compressed on the inward movement of the shaft 10 to store power which, when it is released, furnishes the motive power for the hammering stroke. This is of great advantage in the apparatus as the driving motor is not periodically, at very close intervals, subjected to the load which it would have to take care of with each hammer stroke. The structure is simplified, made more accurate and certain in operation and the apparatus is more durable in operation so that its life of service is lengthened.

The invention is defined in the appended claims and is to be considered comprehensive of all forms of structure coming within their scope.

I claim:

1. In a tool of the class described, a support, an elongated hammer shaft slidably mounted on said support and extending beyond an end thereof, a hammer at the outer end of the shaft, a

rotatable cam mounted on the support, means to continuously rotate the cam, cooperating means on said shaft engageable with said rotatable cam for moving the shaft inwardly and then projecting it forcefully outward with each rotation of the cam, said hammer shaft at its outer portion having an elongated axial opening therein open at its outer end, a nut having an axial opening screw connected with said shaft at its outer end, said hammer having a rod passing through said nut, a member located within the shaft opening screw connected to the inner end of the rod, and compression spring means between said nut and member at their adjacent ends.

2. In a tool of the class described, a support, a hammer shaft reciprocably mounted on the support, a hammer at an end of the shaft, a connection between the hammer and shaft comprising, means for positively moving the hammer away from the support and yieldable means for retracting the hammer, and means for rapidly reciprocating said hammer shaft.

3. The elements of claim 1 combined with means for adjusting the tension of said yieldable means.

4. In a tool of the class described, a support, a hammer shaft reciprocably mounted on said support, a hammer at an end of said shaft outside of said support, an annular collar on said shaft, a circular cam rotatably mounted on said support adjacent said shaft, means for rotating said cam, and an annular cam groove in said cam, said collar extending into said cam groove and said cam groove being on the order of twice as wide as the thickness of said collar, and a connection between said hammer shaft and hammer comprising, means for positively moving the hammer away from the support and yieldable means for retracting the hammer.

HARRY E. GIBSON.
